UNITED STATES PATENT OFFICE.

CHARLES S. BUSHNELL, OF ROCHESTER, NEW YORK, ASSIGNOR TO GENERAL RAILWAY SIGNAL COMPANY, OF ROCHESTER, NEW YORK.

BRAKE-APPLYING APPARATUS.

Application filed March 20, 1925. Serial No. 16,937.

This invention relates to brake applying apparatus for railway trains, and more particularly to control apparatus adapted for controlling the brakes of such trains either 5 manually or automatically.

In applying train control to railway systems, it has been found expedient to use the same device for effecting a brake application automatically as that used by the engineer for effecting a brake application for various reasons some of which will now be given. If an automatic brake application is made by suitable train control apparatus it is essential that the engineer should not 10 be permitted to annul such a brake application by recharging the brake pipe and for this reason the engineer's brake valve itself is preferably moved as far as the lap position at least. If a predetermined reduction 15 only in brake pipe pressure is to be made the same device is preferably used so that a second predetermined reduction is not made on top of the first predetermined reduction, and further it is desirable to effect 20 an automatic brake application and manual brake application by the same device so that, by reason of the fact that since automatic brake applications only seldom occur, and if the same device is used for effecting a 25 manual and an automatic application the mechanism does not stand idle as much but is operated repeatedly by the engineer when making a manual brake application. It has 30 been experienced in the application of automatic train control to railways that a two-stage brake application is much safer in preventing break-in-twos and buckling of trains when an automatic brake application is made. One of the problems confronted 35 in designing brake control mechanism for making a two-stage brake application is the determination of the period of time intervening between the two stages. In order to discuss this further it is considered 40 advisable to review briefly the operation of the usual air brake system.

In the usual air brake system a service 45 brake application is effected by venting the usual equalizing reservoir to a predetermined extent and usually to that pressure at which the auxiliary reservoir pressure equalizes with that of the brake cylinder on an average car. This reduction in equalizing reservoir pressure causes the

equalizing discharge piston valve located directly under the engineer's brake valve to open and discharge brake pipe pressure until the brake pipe pressure has been reduced to that of the equalizing reservoir pressure. This equalizing discharge piston valve is designed so that this valve gradually closes as the pressure in the brake pipe approaches that of the pressure on the other side of the piston, namely, the equalizing reservoir pressure, consequently the blowing off of air is tapered, so to speak, and the rate of discharge is not in proportion to pressure only but is dependent on the pressure in the brake pipe and the opening afforded by this equalizing discharge piston valve. Since the flow of air from the brake pipe through this equalizing discharge piston valve is tapered as just explained, a two-stage brake application even though the second stage starts immediately after the first stage has been completed, is different from a single stage brake application effecting the same reduction in brake pipe pressure; this being true because in the two-stage brake application the pressure above the equalizing discharge piston is reduced say half as much in each stage, so that two tapering discharge periods transpire, whereas if a single reduction is made a single taper discharge period transpires. Obviously, the effect of two light tapering discharges of air from the brake pipe will have a different effect on the triple valves of the cars of the train than will one heavy tapering discharge. Bearing this discussion in mind, it readily appears that the second stage reduction might even be started before the first reduction stage has been completed, and still effect a brake application that is different from a single stage brake application.

One of the reasons for employing a two-stage brake application is that the slack between cars shall first be taken up before a heavy brake application takes place, so as to avoid buckling of the train; and since the taking up of the slack depends upon the length of the train, the grade of the track, the speed of the train and the like, it is difficult to determine how the two reductions of a two-stage application should be spaced; this same thing also being true of break-in-twos. Net, it is difficult to de-

termine definitely just what kind of a two-stage brake application should be made to suit the various conditions encountered in practice.

5 In accordance with the present invention it is therefore proposed to either start the second reduction a predetermined time after the first reduction has been started, which may be varied according to the length of 10 the train and the particular grade on which the train is traveling at the time, to have this time fixed for all conditions or to have the second stage reduction start immediately after the first stage has been completed.

More specifically it is proposed in accordance with the present invention to modify the usual engineer's brake valve by closing up the usual equalizing reservoir service exhaust port and adding a supplemental valve which vents the equalizing reservoir into one or more closed reduction reservoirs when the engineer's brake valve is in the service position, and to vent these reduction reservoirs to atmosphere when the engineer's 20 brake valve is in the release or running position and possibly also when in the lap position; to provide automatic means for operating the usual engineer's brake valve 25 and this supplemental valve to the service position and during such operation unlatch the handle of the engineer's brake valve so that the engineer can not prevent the automatic operation taking place and also to 30 avoid injury due to automatic movement of such handle; and to provide means for connecting the two reduction reservoirs together a suitable period of time after an automatic 35 brake application is initiated.

40 As a further object of the present invention it is proposed to provide means for penalizing the engineer if he does not anticipate the automatic means in starting a brake application or does not properly control the train.

45 Other objects, purposes and characteristic features of the invention will in part be pointed out in the description hereinafter and in part be obvious from the drawings.

50 In describing the invention in detail reference will be made to the accompanying drawings in which:—

55 Fig. 1 is a top view of a well known and standard form of engineer's brake valve for automatic air brake systems, having a brake valve actuator and supplemental valve mechanism superimposed thereon;

60 Fig. 2 is a sectional elevation of the mechanism shown in Fig. 1 taken on the line 2—2 of Fig. 1;

65 Fig. 3 is a horizontal sectional view of the mechanism shown in Figs. 1 and 2 taken on the line 3—3 of Fig. 2;

Fig. 4 is another horizontal section of this mechanism taken on the line 4—4 of Fig. 2;

Fig. 5 is a vertical section of the cut-out cock and air strainer of the mechanism taken on the line 5—5 of Fig. 4;

Figs. 6, 7, 8 and 9 show the ports of the supplemental service valve for the release, 70 lap, service and emergency positions of the engineer's brake valve, respectively, the seat of this valve being shown in dotted lines in Fig. 1;

Fig. 10 shows the combined manual and 75 automatic brake applying mechanism connected to an air brake system for effecting a one-stage predetermined reduction in brake pipe pressure upon an automatic application of the brakes, and either a predetermined 80 reduction or a reduction in excess of such predetermined reduction by a manual brake application;

Fig. 11 shows some of the ports and cavities in the seat and the rotary valve of the 85 usual engineer's brake valve which valve has been slightly modified for adapting such valve for the combined manual and automatic brake applying mechanism embodying the present invention; 90

Fig. 12 shows brake applying means constructed and arranged whereby a brake applying device may either be operated manually or automatically, and which mechanism if operated automatically by suitable train 95 control mechanism effects a predetermined reduction in brake pipe pressure by a two-stage reduction, wherein the second stage reduction is started when the brake pipe pressure by discharging through the usual 100 equalizing discharge piston valve has been reduced substantially to equalizing reservoir pressure; and,

Fig. 13 shows a modified arrangement of 105 the brake applying mechanism from that shown in Fig. 12, in which the second stage reduction is started when the brake pipe stops discharging through the equalizing discharge piston valve.

In describing the invention the usual engineer's brake valve as modified together with the actuator and supplemental service exhaust valve will first be described in detail, after which the various brake applying systems in which these devices are used will be 115 described.

Brake valve and actuator structure.

Referring particularly to Figs. 1 to 5 the body 1 of the usual engineer's brake 120 valve which may be assumed to be the Westinghouse type H6 brake valve is shown, in which the usual rotary valve 2 and the usual valve stem 3 project therefrom. On the body portion 1 is shown a modified form 125 of cap member or main frame 4 having integral therewith the various flanges necessary to support the actuator, and having a notched sector 5 projecting horizontally therefrom into which the latch plunger 6 130

associated with the engineer's brake valve handle 7^a may engage. On the flange just mentioned are bolted the cylinders 10 and 11 of the automatic brake valve actuator which contain pistons 13 and 14. It should be noted that the pistons are of different diameter so that different forces are exerted thereby when the pressure in both of the cylinders is the same, whereby the 10 pistons normally assume the position shown in Fig. 3 when the same pressure is present in both of the cylinders. These pistons are connected by a rack 15 containing gear teeth 16, this rack being guided by the rounded 15 end of a screw plug 17 engaging a slot in the rack 15.

Referring particularly to Fig. 2, the squared portion 3^a of the usual valve stem 3, the upper threaded end of which is not used while the actuator is employed but is only used when the brake valve is employed in the usual way, engages a squared opening in the supplemental valve stem 20, this valve stem having a slot in the top end 25 thereof which cooperates with the off-set splined extension 22^a of the supplemental service exhaust valve 22, this valve in practice being partially held downward on its seat by the compression spring 23 contained 30 in pockets formed in this supplemental service exhaust valve 22 and in the cap member 24. The splined extension 22^a is purposely off-set from the center line, as shown, so that this valve can be placed in position in 35 one way only. This cap member 24 is fastened by five cap screws 25 to the actuator casting including the cylinders 10 and 11 heretofore mentioned a gasket 26 being 40 interposed between this cap and casting. It should be noted at this time that the supplemental valve stem 20 is provided with oil holes 27 which cooperate with the main oil space 28 containing an oil plug 29, a drip lug 30 being provided so that the flow of oil 45 to the various parts to be oiled is properly proportioned.

It is thus noted that the main rotary valve 2 of the engineer's brake valve is directly 50 mechanically connected to the supplemental service exhaust 22. Rotatably mounted about the lower end of the supplemental valve stem 20 is a handle plate 7 which is integral with the engineer's brake valve handle 7^a; whereas near the top of this 55 supplemental valve stem 20 is rotatably mounted the actuator pinion 33 which has teeth engaging the teeth 16 of the rack 15, so that, this actuator pinion rotates in accordance with the movement of the rack 15 and pistons 13 and 14. Just below the 60 actuator pinion 33 and above the handle plate 7 the supplemental valve stem 20 is provided with a projecting lug 34 (see Fig. 4), and a pair of spaced ears 35. Between 65 the ears 35 is pivotally secured a latch mem-

ber 36 which is held in its normal position by a compression spring 37 contained on a guide pin 38 and having its end bearing against the head of this pin 38 and a pocket 39 formed integral with the supplemental 70 valve stem 20, so that the latch is urged into the normal position in which it has been shown. This lug 34 and latch member 36 are adapted to be engaged by various parts of the handle plate and the actuator pinion, 75 so that the supplemental valve stem 20 may be operated by either of these two mechanisms.

In the particular arrangement shown the lug 34 is normally engaged by a lug 42 projecting upwardly from the handle plate 7 and at times this lug 34 is engaged with a lug 43 depending from the actuator pinion 33 (see Figs. 3 and 4), this lug 43 not extending down far enough to strike the lug 42 on the handle plate 7 during automatic operation of this pinion 33. From the actuator pinion 33 there is also depending a pin 44 which however is not long enough to strike the lug 34 but is adapted to strike 80 the cammed end portion of the latch member 36, so that engagement of this pin 44 with the cam portion of the latch member 36 causes the latch to be moved to a position 85 so that its other end gets out of engagement with the circular cam 47 projecting upwardly from the handle plate 7. From this it readily appears (see Fig. 4), when the actuator pinion 33 (see Figs. 2 and 3) and the lug 43 and pin 44 depending from this 90 pinion 33 move in a counter-clockwise direction, that the pin 44 first engages the latch member 36 so as to move it out of latching engagement with the circular cam 47 and immediately thereafter the lug 43 of this 95 actuator pinion engages the lug 34 projecting from the supplemental valve stem 20 and causes this valve stem together with the two valves operatively connected thereto to move in a counterclockwise direction, all 100 without moving the engineer's brake valve handle which has now been unlatched from the remaining mechanism. The various parts such as the length of the stroke of the rack 15, the diameter of the actuator pinion 33 etc., are so chosen that when the pistons 13 and 14 move to the extreme left hand position the engineer's brake valve is 105 moved to the service position (see Fig. 4). Further, it should be noted that during this movement of the valves by the actuator mechanism, although the engineer's brake valve handle 7^a is disconnected from these 110 valves, the engineer may move these valves to the emergency position, this being effected by re-engagement of the lug 43 with the lug 34 when the engineer's brake valve handle follows up the movement of the 115 valve and is moved beyond the service position, further that return of the handle after 120 125 130 135

being moved to the service position does not re-engage the latch.

The front wall of the actuator casting is provided with a cover plate 50 (see Figs. 3 and 10) which cover plate supports electrical switch mechanism. This mechanism consists of a stationary contact 51 supported by an insulating plate 52 and a movable contact 53 having a roller 54 pivotally secured thereto which contact is also supported by this insulating plate 52, these contacts 51 and 53 are normally in engagement with each other but are so located adjacent the handle plate 7 that the lug 56 projecting upwardly from the handle plate 7 (see Fig. 3) causes these contacts to separate when the engineer's brake valve handle 7^a is in either the lap or service position. In other words, switch mechanism is provided which is capable of normally closing a circuit and opening this circuit or vice versa, if the brake valve handle is moved into the lap or service or in any other position if desired manually but not opening such contacts if the valves are moved to such positions automatically.

In order that the engineer may at all times be informed as to the operated position of the brake valve actuator, an indicator is provided for this purpose. This indicator 58 (see Figs. 1, 2 and 3) is secured to the shaft 59 containing the small pinion 60 which is in engagement with the actuator pinion 33, so that the indicator 58 moves in response to the movement of the pistons 13 and 14 and the rack 15. It should be noted that this indicator 58 is not only visible, but projects from the casing and its position may be determined in the dark by feeling the direction in which the pointer or indicator 58 points. Also, this indicator 58 is so small that the actuator can not possibly be prevented from operating the valve by blocking the indicator, for if this were done, it would break due to the fact that it has been purposely designed not to be able to resist the forces transmitted by the actuator.

Having now discussed the various movable parts of the supplemental valve mechanism and brake valve actuator, let us consider the various ports and passages through which air may flow to the various parts of the mechanism. Referring to Fig. 2 it will of course be remembered by those skilled in the art of air brakes that the space directly over the usual rotary valve of the engineer's brake valve is connected to main reservoir pressure, and it will be noted that the cap member 4 as well as the actuator casting containing cylinders 10 and 11 are provided with a passage 62 as shown in dotted lines, so that main reservoir pressure may flow from the top of the rotary valve to the right hand or small cylinder 10. Also, that this passage 62, shown in dotted lines, extends

along the two cylinders 10 and 11, and terminates in the top of the strainer housing (see Figs. 2 and 5), containing the strainer 63 from whence air may flow through the passage 64 into the passage 65 leading to the large cylinder 11 when the cut-out cock 66 is turned to its abnormal or cut-out position. The two cylinders are connected to main reservoir pressure, through these passages, 62, 64, and 65 when the cut-out cock is turned to the cut-out position, to which it may only be turned after the seal 67 is broken and the pin 68 (see Fig. 4) has been moved out of the plane of movement of the cut-out cock 66. Referring to Fig. 5, it should be noted that the passage 65 is normally connected to the pipe 69 which leads to the electro-pneumatic valve EPV shown in Figs. 10, 12, and 13. The retaining pin 57 (see Fig. 4) is provided to keep pin 68 from dropping out altogether when the seal 67 is removed.

Referring to Fig. 1, it readily appears that the cavity 70, the cavity 71, and the exhaust hole 72 are connected to the equalizing reservoir passage 73, the reduction reservoir passage 74 and the exhaust passage 75 leading to atmosphere respectively.

In order to clearly understand the functioning of this supplemental service exhaust valve, attention is directed to Figs. 6, 7, 8 and 9 which show this valve in the release, the lap, service and emergency positions respectively. These cavities in the valve are shown slightly wider than the cavities and openings 70, 71 and 72 contained in the seat so that they may be readily distinguished from each other. The supplemental valve 22 contains only two cavities, namely, the valve seating cavity 76 and the exhaust cavity 77. The valve seating cavity 76 (see Fig. 2) is connected to the top of the valve by the hole 78, and since this cavity 76 is always in communication with cavity 70, which is connected to equalizing reservoir pressure this equalizing reservoir pressure is maintained on top of the supplemental service exhaust valve so as to maintain the proper pressure on this valve to hold it on its seat.

Referring to Figs. 6, 7, 8 and 9 it readily appears that the reduction reservoir passage 74 is connected to the exhaust passage 75 leading to atmosphere at the release position (see Fig. 6), and obviously at all positions between the release and lap positions, namely the running and holding positions, (see Fig. 4); and that the equalizing reservoir passage 73 is connected to the reduction reservoir passage 74 when the supplemental service exhaust valve 22 is in either the service or the emergency position (see Figs. 8 and 9). From this it readily appears that the reduction reservoir passage is connected to atmosphere for all positions of the engineer's

valve to the left of the service position and that the equalizing reservoir passage is connected to the reduction reservoir passage for all positions of the engineer's brake valve 5 to the right of the lap position.

It may be pointed out at this time that the passage through which the reduction reservoir R is exhausted to atmosphere, including port 77 and openings 71 and 72, is so large that the reduction reservoir completely discharges if the valve is moved to the release position long enough to release the brakes, this to avoid the possibility of releasing the brakes without getting the reduction reservoir in condition for another full service brake application.

Structure (Fig. 10).

Referring to Fig. 10, the brake applying mechanism just described is shown connected to a braking system including an equalizing reservoir 80 and a reduction reservoir R , and this mechanism is controlled by an electro-pneumatic valve EPV which is normally energized by a circuit including a contact 82. This contact 82 conventionally illustrates a contact operated by suitable train control mechanism, which opens when an automatic brake application is to be effected and may be opened when the speed of the train is excessive, when the train passes a point along the track under predetermined traffic conditions ahead, and may open when the engineer does not properly control the train or manifest his vigilance in some way or another, or may open if any one of these conditions transpire, this circuit being energized by a suitable source of energy having a terminal B and having its other terminal connected to a common return wire C. This electro-pneumatic valve EPV normally admits pressure from the main reservoir MR through pipes 83 and 69 to the left hand or large cylinder 11 of the brake valve actuator, and with this device EPV de-energized, the spring 84 together with gravity causes the valve to assume its abnormal position and thereby connect this left hand cylinder 11 of the brake valve actuator to atmosphere through exhaust pipe 85.

Manual operation (Fig. 10).

Let us first consider a brake application made by the mechanism shown in Fig. 10 when this mechanism is operated manually. Under normal conditions of the apparatus the brake pipe BP and the equalizing reservoir 80, contain air pressure of a predetermined value depending on the adjustment of the feed valve (not shown) which permits the flow of air from the main reservoir MR (not specifically shown) to the brake pipe until it is charged to a certain value when the engineer's valve is in the normal running position through the medium of

cavity 87 in the rotary valve in the usual engineer's brake valve (see Fig. 11) which need not be discussed specifically; also, under this condition the brake pipe is connected to the equalizing reservoir through 70 the cavity 88, and further main reservoir pressure exists in the small cylinder 10 for reasons heretofore given and pressure exists in the large left hand cylinder 11 by reason of the energized condition of the EPV. 75 Net, the actuator mechanism assumes its normal position as shown in Figs. 1 to 4 inclusive and the supplemental service exhaust valve 22 has its ports in a position to blank the equalizing reservoir and connect 80 the reduction reservoir to atmosphere. If now, the engineer moves his brake valve handle to the service position to effect a brake application the exhaust cavity 77 of the supplemental valve is moved to a position 85 to cut off the exhaust port 72 from the reduction reservoir port 71 and connect this reduction reservoir port 71 to the equalizing reservoir port 70 through the passage 73 having a restricting bushing 73^a therein, this 90 restricting bushing being provided to restrict the flow of air from the equalizing reservoir to the proper rate. When the valve is moved to the service position as just explained, the usual ports in the engineer's rotary valve and seat cause the equalizing reservoir to be isolated from the brake pipe and also the brake pipe to be isolated from feed valve pressure; and with the supplemental service exhaust valve moved to the 95 service position, air may flow from the equalizing reservoir 80 to the reduction reservoir R until the pressure has equalized between 100 these reservoirs, thereby effecting a reduction depending on the ratio of the volumes of both of these reservoirs to that of the equalizing reservoir alone, which ratio is such as to give a full service reduction. This, in turn, causes the brake pipe to be vented until it has dropped to this equalized pressure through the usual equalizing discharge piston 89 located below the standard engineer's brake valve (see Fig. 10). In this connection, it should be remembered that the usual equalizing reservoir service exhaust port in the seat of the usual engineer's brake valve has been closed by the screw plug 61 so that the equalizing reservoir can not be vented to atmosphere through the usual passages provided for this purpose. 115

If the engineer desires to make a further reduction below that of the predetermined reduction, which is seldom if ever necessary, he may move his handle to the lap position and thereby (see Fig. 7) cause the reduction 120 reservoir to be disconnected from the equalizing reservoir and be vented to atmosphere, after which if the valve is moved to the service position air will again flow from the equalizing reservoir 80 to the reduction res- 125 130

ervoir R until a new equalizing pressure lower than the previous equalizing pressure has been reached.

In this connection it is desired to be pointed out that if the engineer wants to split his application, so to speak, by making several successive reductions and by returning to the lap position between these reductions, the engineer will be required to return his handle to the lap position when the desired reduction has been made. This, because air has been permitted to escape from the reduction reservoir, and if the handle is finally left in the service position an excessive reduction is made. This is, however, not true of the braking mechanism shown in Fig. 14.

If the engineer now wishes to release the brakes he may move to either the running or the release position and in so doing he recharges the brake pipe in the same way as is done in the usual air brake system, this movement to the release position also again connects the equalizing reservoir to the brake pipe so that the equalizing reservoir will also be recharged, and also such movement causes the reduction reservoir to be discharged to atmosphere, for reasons given heretofore.

30 Automatic operation (Fig. 10).

Let us assume that by reason of excessive speed, or for some other reason, contacts 82 are opened by the automatic train control apparatus (not shown) and the device EPV is de-energized for the purpose of effecting an automatic brake application. With the device EPV in its de-energized position the large cylinder 11 is vented to atmosphere through pipes 69 and 85, so that the force acting on the large piston ceases and no longer predominates the force acting on the small piston, and the pressure in the small cylinder 10 forces the rack 15 toward the left. During the initial idle movement of the rack 15 the actuator pinion turns loosely without changing the positions of the two valves. This lost motion is necessary in order to permit the engineer to move the usual rotary valve and the supplemental valve from the normal running position to the holding and release positions without being obstructed by the automatic means when normal. Upon a slight further rotation of the actuator pinion 33 in the counter-clockwise direction the pin 44 depending from this pinion 33 strikes the cam portion of the latch member 36 thereby unlatching the handle and upon a slight further movement the lug 43 also depending from this pinion 33 strikes the lug 34 integral with the supplemental valve stem 20. Further movement of the rack and pinion causes the usual rotary valve and the supplemental service valve 22 to rotate with the pinion 33, and

when the pinion has reached its ultimate position at which the protruding bolt extending from the large piston strikes the stop 18 contained in the cylinder head of the large cylinder 11 it is stopped. When this position of the rack 15 and pinion 33 is reached, the two valves are in the service position. This causes the usual rotary valve to blank all ports, except the port 86 which now vents the excess pressure head governor pipe to atmosphere as more particularly pointed out hereinafter. In this connection it should be borne in mind that the service exhaust port in the seat of this rotary valve is plugged up by the plug 61 as heretofore mentioned. The supplemental service exhaust valve, however, now is in a position as shown in Fig. 8 so that the equalizing reservoir cavity 70 is in communication with the reduction reservoir cavity 71 through the application and exhaust cavity 77, so that the equalizing reservoir pressure may flow into the reduction reservoir until the pressure between these reservoirs is equalized, as pointed out in connection with the manual operation; thereby effecting a brake application through the action of the equalizing discharge piston valve 89 in response to equalizing reservoir pressure. This brake application brings the train to a stop or a predetermined low speed depending on the train control mechanism operating contacts 82, and if these contacts are again closed the brake valve actuator returns to its normal position by reason of reapplication of main reservoir pressure to the large cylinder 11, but this return movement of the actuator does not return the rotary valves, which valves must be returned by a positive act on the part of the engineer. It should be borne in mind that the engineer may effect an emergency brake application while a service brake application is being made automatically for reasons heretofore given.

Structure (Fig. 12).

In Fig. 12 has been shown a brake applying mechanism in which the brake valve, supplemental service exhaust valve, brake valve actuator, EPV and equalizing reservoir are the same as those heretofore described. Instead of using a single reduction reservoir such as R, two reservoirs R¹ and R² are used. These reservoirs R¹ and R² are normally isolated by the lower valve member 90 of the electrically operated valve EV, this valve being normally energized as shown. The upper valve member 91 of this electrically operated valve EV affords a passage for venting the second reduction reservoir R² to atmosphere through pipe 92 as clearly shown in Fig. 12. In addition to the apparatus heretofore described there are shown in Fig. 12 two slow acting relays 93 and 94 and a pneumatically operated dif-

ferential circuit closer DPC for closing a circuit at one point so long as brake pipe pressure is higher than equalizing reservoir pressure.

This pneumatically operated circuit controlled DPC consists of two bowl-shaped containers 95 and 96 which are closed by diaphragms 97 and 98 so as to form closed chambers. The chambers 95 and 96 are connected to brake pipe pressure and equalizing reservoir pressure respectively by pipes 99 and 100, a differential piston arrangement may of course be used instead of these diaphragms, if desired. The diaphragms 97 and 98 are connected by suitable means such as a bolt or the like 101 which has an insulating collar 102 contained thereon, which collar engages the movable contact of the contacts 103 forming part of this pneumatically operated circuit controller DPV. The container 96 contains a compression spring 104 which is just strong enough to assure that the contacts 103 are open when the pressures in these two chambers 95 and 96 are the same.

Under normal clear traffic conditions of the apparatus shown in Fig. 12, the slow dropping relay 93 is energized because this relay is connected in multiple with the device EPV which receives its energy through the normally closed contact 82 of the train control mechanism. With this relay 93 energized and with the engineer's brake valve in the normal running position and the contacts 53—53 closed, the other slow dropping relay 94 is energized through the following circuit:—beginning at the terminal B of a suitable source of energy such as a battery, contacts 51—53, wire 107, front contact 108 of the relay 93, wires 109 and 110, winding of the relay 94, wire 111 connected to a common return wire C leading to the other side of said source of energy. With this relay 94 energized the electrically operated valve EV is energized by a circuit readily traced in the drawing and including the front contact 112 of the relay 94. As indicated by the legend in Fig. 12 the contacts 51—53 are open only in the lap and service position.

Automatic operation (Fig. 12).

As heretofore mentioned the apparatus shown in Fig. 12 includes the provision of means for effecting a two-stage service application resulting in a definite predetermined reduction in brake pipe pressure. Let us now assume that an automatic brake application is to be effected and that contacts 82 are opened by suitable train control apparatus for this reason. Opening of contacts 82 de-energizes both the device EPV and the relay 93, but by reason of the slow dropping characteristic of the relay 93 its

front contact 108 will remain closed for a time. De-energization of the device EPV causes the brake valve actuator to move the rotary valve and the supplemental service exhaust valve to the service position quickly, effecting a reduction in the pressure in the equalizing reservoir 81 until it has equalized with the pressure in the first reduction reservoir R^1 , for reasons heretofore given. The ratio of volumes of the equalizing reservoir to the first reduction reservoir is such as to effect a 7 or 8 pound reduction upon equalization when these reservoirs are connected as just explained. The reduction in equalizing reservoir pressure causes the differential pneumatically operated circuit closer DPC to close contact 103, because brake pipe pressure in chamber 95 is higher than equalizing reservoir pressure in chamber 96. With these contacts closed, which takes place before the front contact 108 of the relay 93 is dropped, a stick circuit for the relay 94 is completed, which circuit may be traced as follows:—beginning at terminal B, contacts 51—53 on the engineer's brake valve handle, wire 114, contacts 103 operated by the pneumatic circuit controller DPC, wire 115, stick contact 116 of the relay 94, wires 117 and 110, winding of the relay 94, wire 111, to common return wire C, so that the relay 94 is maintained energized in spite of the dropping of relay 93.

As time runs on with the equalizing reservoir pressure lower than brake pipe pressure the brake pipe pressure gradually reduces through the usual equalizing discharge piston valve 89, and when this brake pipe pressure has almost fallen to equalizing reservoir pressure contacts 103 again open. When these contacts 103 open the relay 94 is de-energized, which in turn through the contact 112 de-energizes the electrically operated valve EV. With this valve EV de-energized it moves to its abnormal dropped position quickly, thereby connecting the reduction reservoirs R^1 and R^2 together without allowing appreciable escape of air to atmosphere during seating of the valve 91. With the reduction reservoirs R^1 and R^2 connected together, as just explained, the equalizing reservoir pressure will again be lowered until the pressure between these three reservoirs is equalized. With this further reduction in equalizing reservoir pressure a second stage of reduction in brake pipe pressure takes place. The reduction reservoir R^2 is of such volume that the reduction in equalizing reservoir pressure resulting upon equalization is such as to give a full service brake application without waste of air. It should be noted even though contacts 103 again close as soon as equalizing reservoir pressure is dropped, that closure of these contacts has no effect on the ap-

paratus, because they are contained in a stick circuit for the relay 94 and therefore are not able to pick up this relay 94.

As just brought out in the operation of the apparatus shown in Fig. 12 the second stage of venting of the brake pipe begins shortly after the first stage ends. This, however, causes the brakes of the train to be applied considerably different from what they would be if a single stage brake application resulting in the same degree of venting of the brake pipe were made, because the discharge of brake pipe pressure tapers off, so to speak, as heretofore explained, also, a short lapse of time may separate these stages by reason of lag in the operation of mechanisms of this kind. If the engineer wishes to have the second stage of the brake application overlap with the first stage of brake application, he may do so by moving his handle to the lap or service posit on before the first stage is completed, and thereby drop the relay 94 by opening of contacts 51—53. In other words, the apparatus shown in Fig. 12 affords a two-stage brake application, the second stage of which follows shortly after the first stage and wherein the engineer may have the second stage begin before the first stage has been fully carried out, or he even may start the second stage immediately after the first so that the result is a single stage application.

Manual operation (Fig. 12).

As far as venting the equalizing reservoir 80 into the reduction reservoir R^1 by manual operation of the brake applying mechanism is concerned, the apparatus in Fig. 12 functions the same as that of Fig. 10 already explained. It is however desired to be brought out that manual operation of the brake valve of Fig. 12 to the service position for a time sufficient to make a reduction of say 7 or 8 pounds in equalizing reservoir pressure and its return to the lap position effects opening of contacts 51—53 to cause dropping of the relay 94; also, that this relay 94 remains de-energized so long as the brake valve handle is not moved to the left beyond the lap position. Consequently the relay 94, and in turn the valve EV, remain de-energized so long as the brakes are not released and the reduction reservoirs R^1 and R^2 remain connected together from the time the manual application is started until the brakes are released, so that the reservoirs R^1 and R^2 effect the braking system upon a manual brake application the same as does the single but larger reduction reservoir R in Fig. 10.

Structure (Fig. 13).

The apparatus shown in Fig. 13 is identical to that shown in Fig. 12 except that the differential pneumatic circuit controller

DPC is entirely omitted, and for the contact 103 of this device the contact 120 of a single pressure pneumatic circuit controller PC is substituted. This single diaphragm circuit controller PC is connected to the service exhaust port leading from the engineer's brake valve, that is, the port through which the exhaust from the equalizing discharge piston valve 89 flows, this exhaust flowing through the pipe 121 into the chamber 95^a and out through the service exhaust fitting 31, the service exhaust fitting 31 being removed and being connected to the exhaust outlet of this circuit controller PC. From this it readily appears that as air flows from the exhaust port of the engineer's brake valve a back pressure, so to speak, is set up in the chamber 95^a, so that the contacts 120 are closed so long as air is escaping from the engineer's brake valve. 85

Operation (Fig. 13).

The operation of the apparatus shown in Fig. 13 is the same as that shown in Fig. 12 except that the contact 120 is operated by back pressure due to the exhaust leading from the engineer's brake valve, whereas the contact 103 shown in Fig. 12 is closed so long as equalizing reservoir pressure is higher than brake pipe pressure. Since there must be a flow of air from the engineer's brake valve so long as equalizing reservoir pressure is higher than brake pipe pressure by reason of the construction of the equalizing discharge piston valve, the contacts 103 and 120 function substantially alike, so that the operation of both of these systems is substantially the same. It should be noted, that the engineer may cause the second stage of the brake application to commence before the first stage has been completed in the arrangement shown in Fig. 13 by moving his brake valve handle to the lap or service position while an automatic brake application takes place. 100 105 110

If the engine employing the train control apparatus shown in Fig. 4 is used as a second engine while double heading, the conductor of the train, who is provided with a key for opening the lock 153, will allow the engineer of the second engine to place his combined cut-out cock and double heading cock DC to the cut-out position, in which the train control apparatus on the second train will be ineffective and the double heading cock will be in condition for double heading purposes. 115 120 125

The present invention thus provides brake applying apparatus in which the same rotary valves are used for effecting brake applications manually or automatically, so that this apparatus is repeatedly operated and is therefore not apt to fail to function by reason of rust and gummed up lubrication which might accumulate by reason of infre- 130

quent use; this apparatus being constructed so that if automatically operated a predetermined reduction in brake pipe pressure only is made either by a single or a two-stage 5 brake application and if a manual brake application is to be made, a service application of any degree may be carried out without going to emergency, and wherein an emergency brake application may be made by the engineer in spite of the fact 10 that the automatic apparatus is in position to effect a service application.

Having thus shown and described several specific embodiments of the invention and having shown rather specific apparatus for carrying out the invention, it is desired to be understood that the specific apparatus illustrated has been shown for the purpose of clearly disclosing apparatus whereby the 20 functions underlying the present invention may be carried out, and not with the idea of showing the particular apparatus preferably employed in practice nor setting forth the scope of the present invention. For instance, 25 various changes in the circuit arrangement for controlling the electrically operated valve EV and other changes may be made so long as the function is the same without departing from the scope of the 30 present invention or the idea of means underlying the same.

What is desired to be secured by Letters Patent is:—

1. In a braking system for railway trains of the type in which the brake pipe is normally charged and in which a brake application is effected if brake pipe pressure is reduced; the combination of an equalizing reservoir; a reduction reservoir; a valve member having a cavity, a seat on which said valve member is adapted to move having three openings therein; said openings being connected to the equalizing reservoir the reduction reservoir and to atmosphere respectively, and being so arranged that the reduction reservoir is connected to atmosphere when the valve member is in the normal position, and the reduction reservoir is connected to the equalizing reservoir when said valve member is in the brake applying position; means for manually controlling said valve member; and means for automatically operating said valve member.

2. In a braking system for railway trains of the type in which the brake pipe is normally charged and in which a brake application is effected if brake pipe pressure is reduced; the combination with a main reservoir, a reduction reservoir and an equalizing reservoir; an equalizing discharge piston valve between said equalizing reservoir and said brake pipe for discharging said brake pipe to atmosphere so long as its pressure is above that of the equalizing reservoir; of a movable valve device having ports and

cavities therein; stationary means against which said valve device rides having ports and cavities therein; said ports and cavities being so arranged that when said valve device is in its normal position, said equalizing reservoir is connected to said brake pipe and said reduction reservoir is connected to atmosphere, when said valve is in its service brake applying position said equalizing reservoir is disconnected from the brake pipe but is connected to said reduction reservoir, and when said valve assumes a position intermediate such normal and service position and equalizing reservoir is isolated from both said brake pipe and said reduction reservoir; manually operable means for controlling the operation of said valve device; and automatic means for operating said valve device.

3. In a braking system for railway trains of the type in which the brake pipe is normally charged and in which a brake application is effected if brake pipe pressure is reduced; the combination with a main reservoir, a reduction reservoir and an equalizing reservoir; an equalizing discharge piston valve between said equalizing reservoir and said brake pipe for discharging said brake pipe to atmosphere so long as its pressure is above that of the equalizing reservoir; of a movable valve device having ports and cavities therein; stationary means against which said valve device rides having ports and cavities therein; said ports and cavities being so arranged that when said valve device is in its normal position, said equalizing reservoir is connected to said brake pipe and said reduction reservoir is connected to atmosphere, when said valve device is in its service brake applying position said equalizing reservoir is disconnected from the brake pipe but is connected to said reduction reservoir, and when said valve device assumes a position intermediate such normal and service position said equalizing reservoir is isolated from both said brake pipe and said reduction reservoir and also said reduction reservoir is connected to atmosphere; a handle for operating said valve device; and automatic means for simultaneously moving said valve device to its service brake applying position and for operatively disconnecting said handle from said valve device.

4. In a braking system for railway trains of the type in which the brake pipe is normally charged and in which a brake application is effected if brake pipe pressure is reduced; the combination with an equalizing reservoir, a reduction reservoir and a main reservoir; of an engineer's brake valve of the construction described and usually employed in such type of braking systems except that the equalizing reservoir service discharge port thereof has been plugged up, of

a supplemental valve operatively connected to the brake valve, said supplemental valve connecting said reduction reservoir to atmosphere when said engineer's brake valve
5 is in the running position and connecting said equalizing reservoir to the reduction reservoir through a restricted connection when the engineer's brake valve is in the service position, a handle for operating said
10 valve, and automatic means for operating said valve.

15. In a braking system for railway trains of the type in which the brake pipe is normally charged and in which a brake application is effected if brake pipe pressure is reduced; the combination with an equalizing reservoir, a reduction reservoir and a main reservoir; of an engineer's brake valve of the type described and usually employed in such type of braking systems except that the equalizing reservoir service exhaust port thereof has been plugged up, of a supplemental valve operatively connected to the brake valve, said supplemental valve connecting said reduction reservoir to atmosphere when said engineer's brake valve is in the running position and connecting said equalizing reservoir to the reduction reservoir through a restricted connection when the engineer's brake valve is in the service position, a handle for operating said valves and automatic means for simultaneously disconnecting said handle and operating said valves to the service position.

35 6. In a braking system for railway trains
of the type in which the brake pipe is normally charged and in which a brake application is effected if brake pipe pressure is reduced; the combination with an equalizing reservoir; a reduction reservoir; a valve member having a cavity; a seat against which said valve member is adapted to move having three openings therein; said openings being connected to the equalizing reservoir, the reduction reservoir and to atmosphere respectively, and being so arranged
40 that the reduction reservoir is connected to atmosphere when the valve member is in the normal position, and the reduction reservoir
45 is connected to the equalizing reservoir when said valve member is in the brake applying position; means for manually controlling said valve member; means for automatically operating said valve member; and other automatic means for connecting said reduction reservoir to another reduction reservoir rendered effective after said first mentioned reduction reservoir has been connected to
50 the equalizing reservoir by the automatic means.

60

7. In a braking system for railway trains of the type in which the brake pipe is normally charged and in which a brake application is effected if brake pipe pressure is reduced; the combination with a main reser-

voir; a reduction reservoir and an equalizing reservoir; an equalizing discharge piston valve between said equalizing reservoir and said brake pipe for discharging said brake pipe to atmosphere so long as its pressure is above that of the equalizing reservoir; of a movable valve device having ports and cavities therein; stationary means against which said valve device rides having ports and cavities therein; said ports and cavities being so arranged that when said valve device is in its normal position, said equalizing reservoir is connected to said brake pipe and said reduction reservoir is connected to atmosphere, when said valve is in its service brake applying position said equalizing reservoir is disconnected from the brake pipe but is connected to said reduction reservoir, and when said valve assumes a position intermediate such normal and service position said equalizing reservoir is isolated from both said brake pipe and said reduction reservoir; manually operable means for controlling the operation of said valve device; and automatic means for operating said device, and other automatic means for connecting said reduction reservoir to another reservoir rendered effective after said first mentioned reduction reservoir has been connected to the equalizing reservoir by the automatic means.

8. In a braking system for railway trains of the type in which the brake pipe is normally charged and in which a brake application is effected if brake pipe pressure is reduced; the combination with a main reservoir, a reduction reservoir and an equalizing reservoir; an equalizing discharge piston valve between said equalizing reservoir and said brake pipe for discharging said brake pipe to atmosphere so long as its pressure is above that of the equalizing reservoir; of a movable valve device having ports and cavities therein; a stationary means against which said valve device rides having ports and cavities therein; said ports and cavities being so arranged that when said valve device is in its normal position, said equalizing reservoir is connected to said brake pipe and said reduction reservoir is connected to atmosphere; when said valve is in its service brake applying position said equalizing reservoir is disconnected from the brake pipe but is connected to said reduction reservoir, and when said valve assumes a position intermediate such normal and service position said equalizing reservoir is isolated from both said brake pipe and said reduction reservoir, and also said reduction reservoir is connected to atmosphere; means for automatically operating said valve member, and other automatic means for connecting said reduction reservoir to another reduction reservoir rendered effective after said first mentioned reduction reservoir has been connected to atmosphere; and a means for automatically disconnecting said reduction reservoir from another reduction reservoir after said reduction reservoir has been connected to atmosphere.

nected to the equalizing reservoir by the automatic means.

9. In a braking system for railway trains of the type in which the brake pipe is normally charged and in which a brake application is effected if brake pipe pressure is reduced; the combination with an equalizing reservoir, a reduction reservoir and a main reservoir; of an engineer's brake valve of the type described and usually employed in such type of braking systems except that the equalizing reservoir service exhaust port thereof has been plugged up; of a supplemental valve operatively connected to the brake valve; said supplemental valve connecting said reduction reservoir to atmosphere when said engineer's brake valve is in the running position, and connecting said equalizing reservoir to the reduction reservoir through a restricted connection when said engineer's brake valve is in the service position; a handle for operating said valve; means for automatically operating said valve; and other automatic means for connecting said reservoir to another reduction reservoir rendered effective after said first mentioned reduction reservoir has been connected to the equalizing reservoir by the automatic means.
10. In a braking system for railway trains of the type in which the brake pipe is normally charged and in which a brake application is effected if brake pipe pressure is reduced; the combination with an equalizing reservoir, a reduction reservoir and a main reservoir; of an engineer's brake valve of the construction usually employed for such type of braking systems except that the equalizing reservoir service exhaust port thereof has been plugged up; of a supplemental valve operatively connected to the brake valve; said supplemental valve connecting said reduction reservoir to atmosphere when said engineer's brake valve is in the running position, and connecting said equalizing reservoir to the reduction reservoir through a restricted connection when the engineer's brake valve is in the service position; a handle for operating said valves; and automatic means for simultaneously disconnecting said handle and operating said valves to the service position; and other automatic means for connecting said reduction reservoir to another reduction reservoir rendered effective after the first mentioned reduction reservoir has been connected to the equalizing reservoir by the automatic means.
11. In a braking system for railway trains of the type in which the brake pipe is normally charged and in which a brake application is effected if brake pipe pressure is reduced; in combination an equalizing reservoir and a reduction reservoir; of an engineer's brake valve of the construction
- usually employed in systems of this kind but modified by having cavities and ports for connecting the equalizing reservoir to the reduction reservoir when said brake valve is in the service brake applying position, and for connecting said reduction reservoir to atmosphere when the brake valve is in the normal position; a handle for operating said valve; automatic means for simultaneously operatively disconnecting said handle from said valve and operating said valve to the service position; and other automatic means for thereafter connecting said reduction reservoir to a second reduction reservoir initiated upon operation of said first mentioned automatic means.
12. In a braking system for railway trains of the type in which the brake pipe is normally charged and in which a brake application is effected if brake pipe pressure is reduced; in combination an equalizing reservoir and a reduction reservoir; of an engineer's brake valve of the construction usually employed in systems of this kind but modified by having cavities and ports for connecting the equalizing reservoir to the reduction reservoir when said brake valve is in the service brake applying position, and for connecting said reduction reservoir to atmosphere when the brake valve is in the normal position; a handle for operating said valve; automatic means for simultaneously operatively disconnecting said handle from said valve and operating said valve to the service position; a second reduction reservoir; an electro-pneumatic valve in a pipe connecting said reduction reservoirs which valve if energized isolates said reservoirs; and means initiated upon automatic operation of said automatic means for de-energizing said electro-pneumatic valve and thereby connecting the two reduction reservoirs together.
13. In a braking system for railway trains of the type in which the brake pipe is normally charged and in which a brake application is effected if brake pipe pressure is reduced; in combination an equalizing reservoir, and a reduction reservoir; of an engineer's brake valve of the construction usually employed in systems of this kind but modified by having cavities and ports for connecting the equalizing reservoir to the reduction reservoir when said brake valve is in the service brake applying position and for connecting said reduction reservoir to atmosphere when the brake valve is in the normal position; a handle for operating said valve; automatic means for simultaneously operatively disconnecting said handle from said valve and operating said valve to the service position; a second reduction reservoir; an electro-pneumatic valve in a pipe connecting said reduction reservoirs which valve if energized isolates

- said reservoirs; a contact in the circuit for energizing said electro-pneumatic valve closed so long as brake pipe pressure is higher than equalizing reservoir pressure.
14. In a braking system for railway trains of the type in which the brake pipe is normally charged and in which a brake application is effected if brake pipe pressure is reduced; in combination an equalizing reservoir, and a reduction reservoir; of an engineer's brake valve of the construction usually employed in systems of this kind but modified by having cavities and ports for connecting the equalizing reservoir to the reduction reservoir when said brake valve is in the service brake applying position, and for connecting said reduction reservoir to atmosphere when the brake valve is in the normal position; a handle for operating said valve; automatic means for simultaneously operatively disconnecting said handle from said valve and operating said valve to the service position; a second reduction reservoir; an electro-pneumatic valve in a pipe connecting said reduction reservoirs which valve if energized isolates said reservoirs; a contact in the circuit for energizing said electro-pneumatic valve closed so long as there is air discharging from the service exhaust port of the engineer's brake valve.
15. In a braking system for railway trains of the type in which the brake pipe is normally charged and in which a brake application is effected if brake pipe pressure is reduced; in combination an equalizing reservoir, and a reduction reservoir; of an engineer's brake valve of the construction usually employed in systems of this kind but modified by having cavities and ports for connecting the equalizing reservoir to the reduction reservoir when said brake valve is in the service brake applying position, and for connecting said reduction reservoir to atmosphere when the brake valve is in the normal position; a handle for operating said valve; automatic means for simultaneously operatively disconnecting said handle from said valve and operating said valve to the service position; a second reduction reservoir; an electro-pneumatic valve in a pipe connecting said reduction reservoirs which valve if energized isolates said reservoirs; a contact in the circuit for energizing said electro-pneumatic valve, closed after the lapse of a predetermined interval of time after said automatic means is rendered active.
16. In a braking system for railway trains of the type in which the brake pipe is normally charged and in which a brake application is effected if brake pipe pressure is reduced, the combination with an engineer's brake valve of the type usually employed in systems of this type having an equalizing discharge piston valve and a pneumatically operated circuit controller which assumes an operated position so long as air is discharging from said equalizing discharge piston valve.
17. In a braking system for railway trains of the type in which the brake pipe is normally charged and in which a brake application is effected if brake pipe pressure is reduced; the combination with an equalizing reservoir, a reduction reservoir and a main reservoir; of an engineer's brake valve of the construction usually employed for such type of braking systems except that the equalizing reservoir service exhaust port thereof has been plugged up; of a supplemental valve operatively connected to the brake valve; said supplemental valve connecting said reduction reservoir to atmosphere when said engineer's brake valve is in the running position, and connecting said equalizing reservoir to the reduction reservoir through a restricted connection when the engineer's brake valve is in the service position; a handle for operating said valve; automatic means for operating said valve; and other automatic means for connecting said reduction reservoir to a second reduction reservoir comprising, an electro-pneumatic valve which if de-energized connects the two reduction reservoirs together, a stick relay having a pick-up circuit and a stick circuit, said pick-up circuit including a contact opened upon initiation of said first mentioned automatic means and a contact closed when the engineer's brake valve is in its normal running position in series, and said stick circuit including a contact closed when the engineer's brake valve is in the normal position and a contact closed so long as brake pipe pressure is higher than equalizing reservoir pressure in series.
18. In a braking system for railway trains of the type in which the brake pipe is normally charged and in which a brake application is effected if brake pipe pressure is reduced; the combination with an equalizing reservoir; a reduction reservoir and a main reservoir; of an engineer's brake valve of the construction usually employed for such type of braking systems except that the equalizing reservoir port thereof has been plugged up; of a supplemental valve operatively connected to the brake valve; said supplemental valve connecting said reduction reservoir to atmosphere when said engineer's brake valve is in the running position and connecting said equalizing reservoir to the reduction reservoir through a restricted connection when the engineer's brake valve is in the service position; a handle for operating said valve; automatic means for operating said valve; and other automatic means for connecting said reduction reservoir to a second reduction reservoir comprising, an electro-pneumatic

- valve which if deenergized connects the two reduction reservoirs together, a stick relay having a pick-up circuit and a stick circuit, said pick-up circuit including a contact opened upon initiation of said first mentioned automatic means and a contact closed when the engineer's brake valve is in its normal running position in series, and said stick circuit including a contact closed when the engineer's brake valve is in the normal position and a contact closed so long as air is being discharged from the service exhaust port of the engineer's brake valve in series.
19. In an automatic train control system for trains employing braking systems of the type in which the brake pipe is normally charged and in which a brake application is effected if brake pipe pressure is reduced, a valve member having a cavity, a seat against which said valve member is adapted to move having three openings therein; said openings being connected to the equalizing reservoir the reduction reservoir and to atmosphere respectively, and being so arranged that the reduction reservoir is connected to atmosphere when the valve member is in the normal position, and the reduction reservoir is connected to the equalizing reservoir when said valve member is in the brake applying position; means for manually controlling said valve member permitting the engineer effecting equalizing reservoir pressure reduction in several stages; means for automatically operating said valve member and for inflicting a penalty upon the engineer; and means for preventing the infliction of such penalty if the engineer has manually moved said valve device to the brake applying position and is holding it there, or the brake pipe is being vented by reason of the fact that this valve device has been in the brake applying position.
20. In an automatic train control system for trains employing braking systems of the type in which the brake pipe is normally charged and in which a brake application is effected if brake pipe pressure is reduced; a valve member having a cavity; a seat against which said valve member is adapted to move having three openings therein; said openings being connected to an equalizing reservoir, a reduction reservoir and to atmosphere respectively, and being so arranged that the reduction reservoir is connected to atmosphere when the valve member is in the normal position, and the reduction reservoir is connected to the equalizing reservoir when said valve member is in the brake applying position; means for manually controlling said valve member permitting the engineer effecting equalizing reservoir pressure reduction in several stages; means for automatically operating said valve member and for inflicting a penalty upon the engineer; and means for preventing the infliction of such penalty if the engineer has started a brake application before said automatic means is actuated to operate said valve member.
21. In an automatic train control system for trains employing braking systems of the type in which the brake pipe is normally charged and in which a brake application is effected if brake pipe pressure is reduced; a valve member having a cavity; a seat against which said valve member is adapted to move having three openings therein; said openings being connected to an equalizing reservoir, a reduction reservoir and to atmosphere respectively, and being so arranged that the reduction reservoir is connected to atmosphere when the valve member is in the normal position, and the reduction reservoir is connected to the equalizing reservoir when said valve member is in the brake applying position; means for manually controlling said valve member permitting the engineer effecting equalizing reservoir pressure reduction in several stages; means for automatically operating said valve member and for inflicting a penalty upon the engineer; and means for preventing the infliction of such penalty if the engineer has started a brake application before said automatic means is actuated to operate said valve member.
22. In an automatic train control system for trains employing braking systems of the type in which the brake pipe is normally charged and in which a brake application results if brake pipe pressure is reduced; a reduction reservoir and an equalizing reservoir; an equalizing discharge piston valve between said equalizing reservoir and said brake pipe for discharging said brake pipe to atmosphere so long as its pressure is above that of the equalizing reservoir; of a movable valve device having ports and cavities therein; stationary means against which said valve device rides having ports and cavities therein; said ports and cavities being so arranged that when said valve device is in its normal position, said equalizing reservoir is connected to said brake pipe and said reduction reservoir is connected to atmosphere, when said valve device is in its service brake applying position said equalizing reservoir is disconnected from the brake pipe but is connected to said reduction reservoir, and when said valve device assumes a position intermediate such normal and service position said equalizing reservoir is isolated from both said brake pipe and said reduction reservoir, and also said reduction reservoir is connected to atmosphere; means for manually controlling said valve device; means for automatically operating said valve device; means for penalizing the engineer if said valve device is automatically operated; and means for preventing said penalizing means being effective if the engineer anticipates the automatic means in starting a brake application himself.
23. In an automatic train control system

for trains employing braking systems of the type in which the brake pipe is normally charged and in which a brake application is effected if brake pipe pressure is reduced; 5 the combination of a reduction reservoir and an equalizing reservoir; an equalizing discharge piston valve between said equalizing reservoir and said brake pipe for discharging said brake pipe to atmosphere so long as its pressure is above that of the equalizing reservoir; of a movable valve device having ports and cavities therein; stationary means against which said valve device rides having ports and cavities therein; said ports and 10 cavities being so arranged that when said valve device is in its normal position, said equalizing reservoir is connected to said brake pipe and said reduction reservoir is connected to atmosphere, when said valve device is in its service brake applying position said equalizing reservoir is disconnected from the brake pipe but is connected to said reduction reservoir, and when said valve device assumes a position intermediate such 15 normal and service position said equalizing reservoir is isolated from both said brake pipe and said reduction reservoir and also said reduction reservoir is connected to atmosphere; means for manually controlling 20 said valve device; means for automatically controlling said valve device; and means for inflicting a penalty upon the engineer if said valve device is operated automatically while there is no pressure discharging from 25 the equalizing discharge piston valve.

24. In an automatic train control system for trains employing braking systems of the type in which the brake pipe is normally charged and in which a brake application is effected if brake pipe pressure is reduced; 40 a reduction reservoir and an equalizing reservoir; an equalizing discharge piston valve between said equalizing reservoir and said brake pipe for discharging said brake pipe to atmosphere so long as its pressure is above that of the equalizing reservoir; of a movable valve device having ports and cavities therein; stationary means against which said valve device rides having ports and cavities 45 therein; said ports and cavities being so arranged that when said valve device is in its normal position, said equalizing reservoir is connected to atmosphere, when said valve device is in its service brake applying position 50 said equalizing reservoir is disconnected from the brake pipe but is connected to said reduction reservoir, and when said valve device assumes a position intermediate such normal and service position said equalizing reservoir is isolated from both said brake pipe and said reduction reservoir and also said reduction reservoir is connected to atmosphere; means for manually controlling said valve device to effect reduction in equalizing reservoir pressure in several stages; means for automatically operating said valve device; and means for inflicting a penalty upon the 55 engineer, unless the engineer anticipates the automatic means and operates said valve device to a brake applying position manually or the engineer has effected a reduction in equalizing reservoir pressure less than a certain period of time prior to the operation of the means for automatically operating said valve device.

55 26. In an automatic train control system for trains employing braking systems of the type in which the brake pipe is normally charged and in which a brake application is effected if brake pipe pressure is reduced; the combination with an equalizing reservoir, a reduction reservoir and a main reservoir; of an engineer's brake valve of the type described and usually employed in such type of braking systems except that the equalizing reservoir service exhaust port thereof has been plugged up; of a supple- 60

means for automatically operating said valve device; and means for inflicting a penalty upon the engineer, unless the engineer anticipates the automatic means and operates said valve device to a brake applying position manually or the engineer has just effected a reduction in equalizing reservoir pressure to which reduced pressure the brake pipe has not yet fallen through the medium of the equalizing discharge piston 65 valve.

25. In an automatic train control system for trains employing braking systems of the type in which the brake pipe is normally charged and in which a brake application is effected if brake pipe pressure is reduced; a reduction reservoir and an equalizing reservoir; an equalizing discharge piston valve between said equalizing reservoir and said brake pipe for discharging said brake 70 pipe to atmosphere so long as its pressure is above that of the equalizing reservoir; of a movable valve device having ports and cavities therein; stationary means against which said valve device rides having ports and cavities 75 therein; said ports and cavities being so arranged that when said valve device is in its normal position, said equalizing reservoir is connected to said brake pipe and said reduction reservoir is connected to atmosphere, when said valve device is in its service brake applying position said equalizing reservoir is disconnected from the brake pipe but is connected to said reduction reservoir, and when said valve device assumes a position intermediate such normal and service position said equalizing reservoir is isolated from both said brake pipe and said reduction reservoir and also said reduction reservoir is connected to atmosphere; means for manually controlling said valve device to effect reduction in equalizing reservoir pressure in several stages; means for automatically operating said valve device; and means for inflicting a penalty upon the 80 engineer, unless the engineer anticipates the automatic means and operates said valve device to a brake applying position manually or the engineer has effected a reduction in equalizing reservoir pressure less than a certain period of time prior to the operation of the means for automatically operating said valve device.

85 26. In an automatic train control system for trains employing braking systems of the type in which the brake pipe is normally charged and in which a brake application is effected if brake pipe pressure is reduced; the combination with an equalizing reservoir, a reduction reservoir and a main reservoir; of an engineer's brake valve of the type described and usually employed in such type of braking systems except that the equalizing reservoir service exhaust port thereof has been plugged up; of a supple- 90

mental valve connecting said reduction reservoir to atmosphere when said engineer's brake valve is in the running position, and connecting said equalizing reservoir to the 5 reduction reservoir through a restricted connection when said engineer's brake valve is in the service position; a handle for operating said engineer's valve; automatic means for operating said valve; and means for 10 penalizing the engineer if said engineer's valve is moved automatically unless the engineer has just reduced equalizing reservoir pressure to which reduced pressure the brake pipe has not yet fallen as a result of the discharge of pressure from the brake pipe through the equalizing discharge piston valve.

27. In an automatic train control system for trains employing braking systems of the 20 type in which the brake pipe is normally charged and in which a brake application is effected if brake pipe pressure is reduced; the combination with an equalizing reservoir, a reduction reservoir and a main reservoir of an engineer's brake valve of the type described and usually employed in such type of braking systems except that the equalizing reservoir service exhaust port thereof has been plugged up; of a supplemental 25 valve operatively connected to the brake valve; said supplemental valve connecting said reduction reservoir to atmosphere when said engineer's brake valve is in the running position, and connecting said equalizing reservoir to the reduction reservoir through a restricted connection when said engineer's brake valve is in the service position; a handle for operating said engineer's valve; automatic means for operating said valve; and means for penalizing the engineer if said engineer's valve is moved automatically unless the engineer has effected a reduction in equalizing reservoir pressure less than a certain period of time prior to the operation 40 of the engineer's valve by said automatic means.

28. In a braking system for railway trains of the type in which the brake pipe is normally charged and in which a brake application is effected if brake pipe pressure is reduced; the combination with an equalizing reservoir; a reduction reservoir and a main reservoir; of an engineer's brake valve of the type described and usually employed in such type of braking systems except that the equalizing reservoir service exhaust port thereof has been plugged up; of a supplemental valve operatively connected to the brake valve; said supplemental valve connecting said reduction reservoir to atmosphere when said engineer's brake valve is in the running position, and connecting said equalizing reservoir to the reduction reservoir through a restricted connection when 60 said engineer's brake valve is in the service

position; a handle for operating said valve; means for automatically operating said valve; and other automatic means for connecting said reduction reservoir to another reduction reservoir rendered effective after 70 said first mentioned reduction reservoir has been connected to the equalizing reservoir by the automatic means; and means for penalizing the engineer if the engineer's brake valve is operated automatically unless the 75 engineer has made a reduction in equalizing reservoir pressure less than a certain period of time prior to the operation of the valve by said automatic means.

29. In an automatic train control system 80 for railway trains employing braking systems in which the brake pipe is normally charged and in which a reduction in brake pipe pressure effects an application of the train brakes, the combination of brake applying means which if operated automatically effects a brake application due to a predetermined reduction in brake pipe pressure, means for manually operating said brake applying means, and means for penalizing the engineer if he has done nothing toward effecting a brake application by operating said brake applying means manually when said brake applying means has been 90 operated automatically.

30. In an automatic train control system for railway trains employing braking systems in which the brake pipe is normally charged and in which a reduction in brake pipe pressure effects an application of the 100 train brakes; the combination of brake applying means which if operated automatically affects a brake application due to a predetermined reduction in brake pipe pressure obtained in two stages; means for manually 105 operating said brake applying means; and means for penalizing the engineer if said brake applying means has been operated automatically unless the engineer has started a brake application less than a predetermined period of time before said brake applying means was operated automatically.

31. In an automatic train control system for railway trains employing braking systems in which the brake pipe is normally charged and in which a reduction in brake pipe pressure effects an application of the train brakes, the combination of brake applying means which if operated automatically effects a brake application due to a predetermined reduction in brake pipe pressure in two stages, means for operating said brake applying means, and means for penalizing the engineer if said brake applying means has been operated automatically unless the engineer has started a brake application less than a predetermined period of time before said brake applying means was operated automatically, said brake applying means if operated to a brake applying pos- 110 120 125 130

tion manually also effecting a predetermined reduction in brake pipe pressure, and means for penalizing the engineer if said brake applying means is operated automatically.

32. In an automatic brake valve operator, the combination with the usual engineer's brake valve, of means for automatically actuating said valve to the service brake applying position and for simultaneously releasing the operative connection between the brake valve handle thereof and the valve for operation of the valve toward the release position, but maintaining such operative connection for movement of the valve by the handle toward the service and emergency position, and means for indicating when said automatically actuated means is in its normal position.

33. In an automatic brake valve operator, the combination with the usual engineer's brake valve, of means for automatically actuating said valve to the service brake applying position and for simultaneously releasing the operative connection between the brake valve handle thereof and the valve for operation of the valve toward the release position, but maintaining such operative connection for movement of the valve by the handle toward the service and emergency position, said mechanism being constructed so that the engineer is advised when the automatically actuated means is in its normal position.

34. Brake applying apparatus for air brake systems of the type wherein the brake pipe is normally charged and wherein venting of the brake pipe causes an application of the brakes, the combination with a manually operable valve having ports and passages whereby movement of said valve to different positions may effect charging or venting of said brake pipe, and means associated with said valve whereby if said valve is moved to a brake applying position and held there said brake pipe is vented to a predetermined extent only but if said valve is moved to the brake applying position is then partly returned to the normal position and is then again moved to the brake applying position the brake pipe is vented to a greater extent.

35. Brake applying apparatus for air brake systems of the type wherein the brake pipe is normally charged with fluid pressure and wherein venting of the brake pipe effects a brake application; the combination with the usual brake pipe; a main reservoir

containing fluid pressure; and an engineer's brake valve for charging said brake pipe from said main reservoir and venting said brake pipe to atmosphere comprising, a stationary casing having two parallelly arranged valve seats each having a port and a cavity therein, a rotary valve for each of said valve seats each having a port and a cavity therein for cooperation with the port and cavity in its cooperating valve seat, said valves being urged against their respective valve seats by fluid pressure, and a handle common to both of said valves for operating both of said valves simultaneously.

36. Brake applying apparatus for air brake systems of the type wherein the brake pipe is normally charged with fluid pressure and wherein venting of the brake pipe effects a brake application; the combination with the usual brake pipe; a main reservoir containing fluid pressure; and an engineer's brake valve for charging said brake pipe from said main reservoir and venting said brake pipe to atmosphere comprising, a stationary casing having two parallelly arranged valve seats each having a passage therein, a rotary valve for each of said valve seats each having a passage therein for cooperation with the passage in its cooperating valve seat, said valves being urged against their respective valve seats by fluid pressure, and a handle common to both of said valves for operating both of said valves simultaneously.

37. Brake applying apparatus for air brake systems of the type wherein the brake pipe is normally charged with fluid pressure and wherein venting of the brake pipe effects a brake application; the combination with the usual brake pipe; a main reservoir containing fluid pressure; and an engineer's brake valve for charging said brake pipe from said main reservoir and venting said brake pipe to atmosphere comprising, a stationary casing having two parallelly arranged valve seats, a rotary valve for each of said valve seats, said rotary valves having their axis of rotation coincident and said valves being urged against their respective valve seats by fluid pressure, and a handle operable about the axis of said rotary valves and operatively connected to both of said rotary valves, whereby both of said valves are operated simultaneously upon movement of said handle.

In testimony whereof I affix my signature.
CHARLES S. BUSHNELL.
